UNITED STATES PATENT OFFICE

99,148

DESIGN FOR A RADIOCABINET OR SIMILAR ARTICLE

Gail Vandenbraak, San Marino, Calif.

Application March 23, 1935, Serial No. 56,017

Term of patent 3½ years

To all whom it may concern:

Be it known that I, Gail Vandenbraak, a citizen of the United States, residing at San Marino, in the county of Los Angeles and State of California, have invented a new, original, and ornamental Design for Radio Cabinet or Similar Article, of which the following is a specification, reference being had to the accompanying drawing, forming a part thereof.

Referring to the drawing:

The figure is a perspective view of a radio cabinet, showing my new design.

The side of the cabinet not disclosed is similar to the one shown.

Dominant features of my new design reside in the arrangement of the speaker grille so that it almost completely surrounds the dial opening,

and in the provision of a three-branched panel, the surface of which is raised slightly from the adjacent surface of the balance of the cabinet, one branch of this panel extending vertically upwards along the front face of the cabinet, where it embraces the dial opening, and then horizontally along the top of the cabinet to its after face, and the other two branches extending horizontally along the front face of the cabinet adjacent the lower edge thereof and to the front corners of the cabinet, whence they extend along the end walls to the after face of the cabinet.

I claim:

The ornamental design for a radio cabinet or similar article, as shown and described.

GAIL VANDENBRAAK.
